REINFORCED CONCRETE STRUCTURE

Clarence H. Roy, East Cleveland, Ohio, assignor
of one-fourth to William J. Wesseler, East
Cleveland, Ohio

Application May 24, 1934, Serial No. 727,359

16 Claims. (Cl. 61—32)

This invention, as indicated, relates to a reinforced concrete structure. More particularly, it comprises a reinforced skeletonized concrete structure adapted to serve as a dam, levee, reservoir, or the like. The structure is intended to be used in place of mass concrete structures, earth embankments, or composite structures of various types, and to provide a stable yet less costly structure than can be installed by other methods for constructions of equal service life.

The invention is intended to provide structures which may be erected upon soil independently of rock or pile foundations and can be maintained in continuous permanent service upon soils of varying pressure value. The structure itself is of relatively light weight, but owing to its cantilever form of construction will have an effectiveness equal to a mass concrete structure of much greater weight or to a structure securely anchored to heavy foundations. The economy of construction of this type of structure is very great and the savings made possible over other types in the way of materials and labor as well as time of construction makes it highly desirable for projects wherein the cost of the installation is of controlling importance and which nevertheless makes heavy service demands upon the structure. The cost of maintenance is negligible inasmuch as the structure will have an adequate factor of safety for all special stresses such as ice pressure, floods, and the like.

Heretofore it has been the practice in constructing dams of great height intended to hold back large bodies of water, to use mass or cellular reinforced concrete, such dams being supported upon heavy foundations and anchored in rock side walls wherever possible. Such constructions, however, are entirely too expensive for use in impounding water over large relatively flat areas when the structures are more in the nature of levees and where it is impossible to secure adequate rock foundation and wherein the providing of pile foundations is not warranted by the economic circumstances controlling the installation. It has also been the practice to provide inclined concrete walls supported upon inclined struts extending to pile foundations. In other cases it has been the practice to provide inclined walls supported by buttresses which in most instances were required to be splayed adjacent their lower portions so as to cover extended areas or such buttresses have been supported on heavy concrete pads. All of such constructions have been relatively expensive, and in many instances the only protection available for certain areas is

the earth levee which in its unprotected form is always subject to erosion, particularly during times of flood and is therefore a source of danger to lives and property in the vicinity.

The present invention is intended to obviate the difficulties referred to and provide an inexpensive thoroughly dependable concrete structure which is not only cheap to install but which has a permanent service life equal to much more costly structures and which will be able to withstand any degree of flood and to resist the erosive action of swift flowing water in times of emergencies.

The principal object of the present invention is to provide a reinforced concrete structure which does not require separate foundation supporting structures or piling, and wherein cantilever action is made use of to resist stresses which may be imposed upon the structure and prevent displacement thereof.

Another object of the invention is to provide a concrete structure which may be erected by means of portable forms wherein the work may be progressively installed without undue expense for equipment.

A further object of the invention is to provide a structure adapted for use either as a dam, levee, reservoir, or the like, which will require the minimum amount of material for its construction, and which will present the maximum amount of resistance to fracture or displacement for the maximum loads which may be imposed upon the structure.

Another object of the invention is to provide a structure wherein spillways are inexpensively formed and wherein the structure itself is protected against injury through overflow or undercutting.

Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain structures embodying the invention, such disclosed means constituting, however, but several of various forms in which the principle of the invention may be used.

In said annexed drawing:

Figure 1 is a perspective view showing a structure embodying the principles of the invention;

Figure 2 is a top plan view, partly in section, taken along the line 3—3, shown in Figure 1, looking in the direction of the arrows;

Figure 3 is a transverse vertical sectional view of the structure shown in Figure 1; and

Figure 4 is a view similar to Figure 3, taken at the position of the spillway shown in Figure 1.

5 As is clearly shown in the drawing, the preferred form of construction comprises an inclined slab 1 preferably reenforced and extending at an angle of approximately forty-five degrees in order to approximate the maximum of economy of material with an adequate degree of 10 resistance to displacement. The slab is supported at its forward edge upon the upper end of a reinforced cut-off wall 2 and merges with a reenforced floor or apron 3 adapted to act as a cantilever and extending to any desired distance in 15 advance of the cut-off wall to protect the wall against erosion. When the structure is used to form a reservoir, it is customary to provide a concrete floor for the reservoir and the apron in such 20 event is continued over the entire area within the space defined by the walls.

Where the ground pressure is close to the limit of adequate supporting capacity, it is frequently desirable to provide the structure with a row of 25 sheet piling 4 immediately in advance of the cut-off wall, such sheet piling being frequently designated a "tight-row."

The inclined slab is provided centrally of its under side with a longitudinal extension 5 of re-enforced concrete against the under face of which, 30 inclined struts 6 bear at intervals, as will be presently explained. The longitudinal extension, together with the adjacent area 7 of the slab structure may have reenforcing elements in the form of rods 8 and stirrups 9, to provide in effect a longitudinal girder having a high degree of 35 strength extending along the entire central area of the slab. Fillets 10 are preferably formed on the under side of the slab adjacent the extension. The slab itself may be formed of greater thickness 40 below such longitudinal extension and above said extension may be formed of lesser thickness or may be tapered from the thickness of the lower portion to a predetermined thickness adjacent the upper edge in accordance with the water pressure 45 ratios for the corresponding elevations.

The upper edge of the concrete slab is preferably formed with an upstanding parapet or ledge 11, which, as shown in the second panel 50 in Figure 1, may be cut away so as to form a spillway 12 in the event the water against the inclined slab rises to a point above the estimated capacity of the structure. A protecting member or a sluiceway 13 is provided beneath the spillway to direct the overflow away from the 55 footings so as to prevent erosion at such point. If desired, valves (not shown) may open from said sluiceways through the adjacent slab area for flood control, water level regulation, or other 60 purposes. Immediately beneath the parapet the inclined slab is formed with a reenforced longitudinal girder extension 14, the structure forming with the parapet and the reenforcing elements, shown as rods 15 and stirrups 16, a vertical girder adapted to provide a high degree of 65 strength to the structure.

The inclined slab is supported at its lower end, as stated, upon the cut-off wall and is supported at its intermediate portion by means of 70 a series of inclined struts 6 bearing against the longitudinal girder and preferably at equal intervals is supported as to its upper portion by a series of vertical struts 17 bearing against the under face of the top girder. The inclined slab, 75 in addition to the longitudinal reenforcing rods,

is provided with reenforcing rods 18 extending at right angles to said longitudinal rods, the alternate rods of the series of rods 18 being turned outwardly into the apron adjacent its upper surface, and the remaining rods of said series being turned downwardly into the cut-off wall adjacent its forward surface. This provides for cantilever action by both the apron and the cut-off wall. The cut-off wall is preferably reenforced by means of longitudinal rods 19 and stirrups 20. The inclined and vertical struts 6, 17, respectively, merge at a point slightly above the plane of the floor apron and are supported upon an isolated footing which is preferably in the form of a reenforced concrete pad 21 of an area proportionate to the character of the soil upon which it is supported. The isolated footings are preferably formed within trenches which may be below the frost line or the structure may be subsequently covered with earth to the necessary degree to protect the footing from frost beneath its lower surface. The footings as shown are of rectangular construction and are joined to each other by means of longitudinal ties which may be in the form of 25 reinforced concrete girders or "ground beams" 22.

The isolated footings are connected by means of cantilever tie beams 23 with the cut-off wall adjacent the base of the inclined slab, the upper surface of the tie beam being preferably in the plane of the floor in advance of the cut-off wall and in the plane of the top of the isolated footings. The under face of the cantilever beam 23 is inclined upwardly so as to be free of earth pressure which would interfere with its cantilever action. Each of the isolated footings extends rearwardly of the point of support of the vertical and inclined structures to a greater extent than forwardly thereof so as to provide for forward rocking action of the structure when heavy weight is placed upon the inclined slab. This action is carried into the cut-off wall by means of the cantilever tie beam which is suitably reenforced with steel bars 24, and stirrups 25, the reenforcing steel bars being positioned adjacent the lower and upper surfaces of the beam, the steel bars in the lower portions taking the tensile strains. The amount of reenforcing placed within the structure is to be calculated according to the particular strains which it is 50 to resist, and ordinarily no reenforcing or very little reenforcing is required in neutral points of the structure.

When a reservoir is constructed, it is frequently desirable to provide means for supporting a 55 cover thereover and in such event both the isolated footings and the cut-off wall may serve as piers upon which columns for the support of the roof or covering for the reservoir may be erected. Likewise, where an open reservoir is to 60 be provided, it is frequently desirable to have a concrete walk erected about the margins of the basin and in such event columns may be carried upwardly from the parapet and from an adjacent portion of the inclined slab and a concrete walk installed at such point.

The various sizes of the structural elements and the spacing of the footings and struts may be varied in accordance with the service which the structure is intended to provide. For structures intended for use as levees, isolated footings at twelve foot intervals will provide sections or "bays" of sufficient strength to serve all ordinary purposes, the footings in the event satisfactory ground pressure is available being ap- 75

proximately of two foot depth and the inclined slab being approximately ten inches thick adjacent its lower section and of lesser thickness adjacent its upper section. The footing and the 5 cantilever tie beam are preferably formed in shallow trenches and a tapered form is used to provide the inclined under face of the cantilever tie beam, such form being left in the trench and having no supporting effect for the structure as 10 a whole after the cantilever tie beam is completed. It is important to prevent ground pressure bearing against the under face of the cantilever tie beam and with certain types of soil it may be necessary to provide a wall of sheet 15 piling or like construction to prevent interference with the free cantilever action of such beams. The entire structure is free of uplift pressure at all times, being a skeletonized form of construction and having no extended solid 20 masses to confine water beneath the same which might bring into action displacement by hydraulic pressure.

Other modes of applying the principle of my invention may be employed instead of the one 25 explained, change being made as regards the structure herein disclosed, provided the means stated by any of the following claims or the equivalent of such stated means be employed.

I therefore particularly point out and distinctly 30 claim as my invention:

1. A reenforced concrete structure having an inclined slab, a support for the forward edge of said slab comprising a continuous cut-off wall extending into the earth, supports for the upper 35 portion of said slab in the form of struts at spaced intervals, reenforced concrete footings beneath said struts and cantilever beams connecting said footings with said cut-off wall and slab.

2. A reenforced concrete structure having an 40 inclined slab, a support for the forward edge of said slab comprising a continuous cut-off wall extending into the earth, supports for the upper portion of said slab in the form of struts at spaced intervals, reenforced concrete footings beneath 45 said struts, longitudinal tie members connecting said respective footings, and cantilever beams connecting said footings with said cut-off wall and slab.

3. A reenforced concrete structure having an 50 inclined slab, a support for the forward edge of said slab comprising a continuous cut-off wall extending into the earth, an integral longitudinal girder formed on the slab above said forward edge, struts at spaced intervals connected with said integral longitudinal girder, reenforced concrete footings beneath said struts, and cantilever beams connecting said footings with said cut-off wall and slab.

4. A reenforced concrete structure having an 55 inclined slab, a support for the forward edge of said slab comprising a continuous cut-off wall extending into the earth, a plurality of integral longitudinal girders formed on the slab above said forward edge, struts at spaced intervals connected with said respective integral longitudinal girders, reenforced concrete footings beneath said struts, and cantilever beams connecting said footings with said cut-off wall and slab.

5. A reenforced concrete structure having an 60 inclined slab, a support for the forward edge of said slab comprising a continuous cut-off wall extending into the earth, an integral longitudinal girder formed on the slab above said forward edge, struts at spaced intervals connected with said integral longitudinal girder, reenforced con-

crete footings beneath said struts, longitudinal tie members connecting said respective footings, and cantilever beams connecting said footings with said cut-off wall and slab.

6. A reenforced concrete structure having an inclined slab, a support for the forward edge of said slab comprising a continuous cut-off wall extending into the earth, a support for the upper portion of said slab in the form of struts at spaced intervals, reenforced concrete footings beneath 10 said struts and extending rearwardly from the point of support for said struts a greater distance than forwardly therefrom, and cantilever beams connecting said footings with said cut-off wall and slab.

7. A reenforced concrete structure having an inclined slab, a support for the forward edge of said slab comprising a continuous cut-off wall extending into the earth, a support for the upper portion of said slab in the form of struts at 15 spaced intervals, reenforced concrete footings beneath said struts and extending rearwardly from the point of support for said struts a greater distance than forwardly therefrom, and cantilever beams connecting said footings with said cut-off wall and slab, said cantilever beams comprising transverse girders having the under sides thereof tapered upwardly toward said cut-off wall and having reinforcing tension members in the lower inclined portion of said cantilever beams.

8. A reenforced concrete structure having an inclined slab, a support for the forward edge of said slab comprising a continuous cut-off wall extending into the earth, an apron formed as a horizontal continuation of said slab and merging with the upper portion of said cut-off wall, supports for the upper portion of said slab in the form of struts at spaced intervals, reenforced concrete footings beneath said struts, and cantilever beams connecting said footings with said 40 cut-off wall and slab.

9. A reenforced concrete structure having an inclined slab, a support for the forward edge of said slab comprising a continuous cut-off wall extending into the earth, an apron formed as a 45 horizontal continuation of said slab and merging with the upper portion of said cut-off wall, longitudinal reinforcing bars at spaced intervals in said inclined slab, reinforcing bars at right angles to said longitudinal bars within the lower portion of said slab, said bars being continued through the upper portion of said apron and forming a reinforcement therefor, supports for the upper portion of said slab in the form of struts at spaced intervals, reenforced concrete 50 footings beneath said struts, and cantilever beams connecting said footings with said cut-off wall and slab.

10. A reenforced concrete structure having an inclined slab, a support for the forward edge of said slab comprising a continuous cut-off wall extending into the earth, an apron formed as a horizontal continuation of said slab and merging with the upper portion of said cut-off wall, longitudinal reinforcing bars at spaced intervals in 55 said inclined slab, reinforcing bars at right angles to said longitudinal bars within the lower portion of said slab, said bars being continued through the forward portion of said cut-off wall and forming a reinforcement therefor, supports for the upper portion of said slab in the form of struts at spaced intervals, reenforced concrete footings beneath said struts, and cantilever beams connecting said footings with said cut-off wall and slab.

11. A reenforced concrete structure having an inclined slab, a support for the forward edge of said slab comprising a continuous cut-off wall extending into the earth, an apron formed as a horizontal continuation of said slab and merging with the upper portion of said cut-off wall, longitudinally reenforcing bars at spaced intervals in said inclined slab, reenforcing bars at right angles to said longitudinal bars within the lower portion of said slab, one series of said bars being continued through the upper portion of said apron and another series of said bars being continued through the forward portion of said cut-off wall and forming a reenforcement of said apron and wall, respectively, supports for the upper portion of said slab in the form of struts at spaced intervals, reenforced concrete footings beneath said struts, and cantilever beams connecting said footings with said cut-off wall and slab.
12. A reenforced concrete structure having an inclined slab, a support for the forward edge of said slab comprising a continuous cut-off wall extending into the earth, supports for the upper portion of said slab in the form of struts at spaced intervals, reenforced concrete footings beneath said struts, cantilever beams connecting said footings with said cut-off wall and slab, an apron extending forwardly as a continuation of said slab with its upper surface in the plane of said cantilever beams, reenforcing bars extending downwardly through said slab and through said apron, and reenforcing bars extending through the upper portion of said cantilever beams and through said apron.
13. A reenforced concrete structure having an inclined slab, a support for the forward edge of said slab comprising a continuous cut-off wall extending into the earth, supports for the upper portion of said slab in the form of struts at spaced intervals, reenforced concrete footings beneath said struts, cantilever beams connecting said footings with said cut-off wall and slab, an apron extending forwardly as a continuation of said slab with its upper surface in the plane of said cantilever beams, reenforcing bars extending down-
- wardly through said slab and through said apron, reenforcing bars extending downwardly through said slab and into the forward portion of said cut-off wall, and reenforcing bars extending through the upper portion of said cantilever beams and through said apron. 5
14. A reenforced concrete structure having an inclined slab, a support for the forward edge of said slab comprising a continuous cut-off wall extending into the earth, supports for the upper portion of said slab in the form of struts at spaced intervals, reenforced concrete footings beneath said struts, cantilever beams connecting said footings with said cut-off wall and slab, and a depression formed along a portion of the upper 10 edge of said slab to provide a spillway. 15
15. A reenforced concrete structure having an inclined slab, a support for the forward edge of said slab comprising a continuous cut-off wall extending into the earth, supports for the upper portion of said slab in the form of struts at spaced intervals, reenforced concrete footings beneath said struts, cantilever beams connecting said footings with said cut-off wall and slab, a depression formed along a portion of the upper 20 25 edge of said slab to provide a spillway, and a concrete sluiceway formed integrally with the lower portions of the structure beneath said spillway.
16. A reenforced concrete structure having an inclined slab, a support for the forward edge of said slab comprising a continuous cut-off wall extending into the earth, an integral longitudinal girder formed on the slab above said forward edge, struts at spaced intervals connected with said integral longitudinal girder, reenforced concrete 30 35 footings beneath said struts, longitudinal tie members connecting said respective footings, cantilever beams connecting said footings with said cut-off wall and slab, a depression formed along a portion of the upper edge of said slab to provide a spillway, and a concrete sluiceway formed integrally with the lower portion of the struts and resting upon said longitudinal tie members, footings, and adjacent cantilever beams. 40 45
